[57] CLAIM

The ornamental design for an elastic goggle, as shown and described.

DESCRIPTION

FIG. 1 is an isometric view from the front and top of an elastic goggle showing my new design;

FIG. 2 is an isometric view from the back and bottom thereof;

FIG. 3 is a top plan view thereof, the bottom plan view being a mirror image thereof; and,

FIG. 4 is a side elevational view thereof, the other side elevational view being a mirror image thereof.
